(57) **CLAIM**

The ornamental design for a pipe cap as shown and described.

DESCRIPTION

FIG. 1 is an exploded perspective view of a pipe cap showing a first variant of the design;

FIG. 2 is another exploded perspective view thereof;

FIG. 3 is a bottom view thereof;

FIG. 4 is a top view thereof;

FIG. 5 is a side view thereof;

FIG. 6 is an exploded perspective view of a pipe cap showing a second variant of the design;

FIG. 7 is another exploded perspective view thereof;

FIG. 8 is a bottom view thereof;

FIG. 9 is a top view thereof; and,

FIG. 10 is a side view thereof.

The references to "top", "front", "back", "right", "left" and "bottom" in the figure descriptions are not meant to require certain in-use orientation or to limit the design.

The broken lines shown in the drawings illustrate disclaimed subject matter that forms no part of the claimed design.
